METHOD OF AND APPARATUS FOR SAMPLING ANTHRACITE COAL

Arthur N. Brooks, West Springfield, Mass.

Application February 2, 1935, Serial No. 4,678

4 Claims. (Cl. 214—17)

This invention relates to a method of and apparatus for sampling anthracite coal. In the distribution of anthracite coal from the mine, railroad cars are loaded at the breakers, and it has heretofore been impossible to determine an accurate analysis of the anthracite coal in a car, in regard to the proportion of slate and other impurities, due to the difficulty involved in procuring samples for a test. Samples of anthracite coal have been taken from the top of the load and tested, but such tests are not satisfactory evidence of the average contents of the car. Some cars in use will take a nine foot depth of anthracite coal, and the coal, in such a carload, 10 may vary considerably in proportion of impurities, relative to the coal on the upper surface of the load.

It is an object of this invention to provide a method and means for procuring a sample of anthracite coal for analysis from any desired location in a carload, an open pile, or any other form of aggregation of units of anthracite coal.

Broadly, the method involved in this invention comprises first, the introduction of a receptacle 25 into a mass of anthracite coal and other material to be sampled to a predetermined depth and at a chosen location, second, the filling of the receptacle with the material to be sampled, third; the withdrawal of the filled receptacle, and 30 fourth; the discharge of the material in the receptacle at a convenient location for analysis.

It is to be understood that the receptacle used is of definite capacity, as to weight, or volume, as 20 pounds.

A preferred form of apparatus for carrying out the steps in the above process is illustrated in the accompanying drawings, in which:

Fig. 1 is an elevational view of the apparatus, 40 with the sampling receptacle positioned in a loaded anthracite coal car, shown in section.

Fig. 2 is a plan view of the apparatus, shown in Fig. 1.

Fig. 3 is a vertical, sectional view of the receptacle and supporting plunger.

Fig. 4 is a partial, sectional view, similar to Fig. 3, showing the open position of the door latches.

Fig. 5 is a plan, sectional view on the line 5—5 50 of Fig. 3.

Fig. 6 is a plan, sectional view on the line 6—6 of Fig. 3, and

Fig. 7 is a side, elevational view of the receptacle.

Referring now to the drawings in detail, in

which like numerals refer to like parts throughout:

A railroad car 1, filled with anthracite coal 2, is positioned beside a platform 3. A mast 4, mounted on a turntable 5, has pivotally secured thereon at 6, a boom 7. A winch 8 is mounted on the turntable 5 and operated by a reversible motor 9, and cables 10 and 11, connected to the boom 7 at 12 and operatively connected to the winch 8, serve to raise and lower the boom 7, as indicated in Fig. 1. Struts 13, secured to a pivotal bearing 14 on the top of the mast 4 and to foundations 15, brace the mast 4. A plunger shaft 16, pivotally connected at 17 to the outer end of the boom 7, has secured on its lower end a receptacle 18. As indicated in Figs. 1 and 2, the boom 7 may be lowered to sink the receptacle into the anthracite coal and raised to remove the receptacle therefrom, and the boom 7 may be swung to locate the receptacle at any desired spot on the top of the car, and to swing the receptacle onto the platform for unloading. The boom 7 is swung by revolving the turntable 5, either mechanically, by operative connecting means to the motor 9, (not shown), or manually, by means of a lever 19. The plunger 16 may be marked, as indicated in Fig. 1, to show the depth of the receptacle 18 in the coal 2.

Referring to Figs. 3—7, inclusive, the plunger 16 is a tubular member, such as a length of steel pipe, and is secured at its upper end in a bearing member 20, which is pivotally secured at 17 on the outer end of the boom 7. The lower end of the plunger 16 is secured by welding, or other suitable means, in a hub 21. The hub 21 is supported in the center of the receptacle 18 by ribs 22. The top of the receptacle 18 is open, and is normally closed by doors 23 which are hinged at 24 to the side walls 25 of the receptacle 18. In closed position, the doors 23 rest on latches 26, and are thus prevented from being forced inwardly into the receptacle 18 by pressure of coal on top of them. The latches 26 are pivotally supported within the plunger 16 in a clevis 27 and normally project through slots 28, formed in the plunger 16, to engage the doors 23. A contractile spring 29, anchored to a pipe plug 30, secured in the lower end of the plunger 16 and connected to the latches 26 by means of a wire loop 31, normally holds the latches 26 seated on inwardly projecting lugs 32, formed in the plunger 16. A cable 33, secured in the clevis 28 and guided by sheaves 34 and 35, pivotally secured in the plunger 16 and on the boom 7, respectively, provides means for raising the latches 26 to release the doors 23, as indicated

in Fig. 4. A plug 36 is secured to the plunger 16 to limit the upward movement of the clevis 21, thereby preventing disengagement of the latches 26 in the slots 28.

5 Doors 37, hinged at 38 to the bottom of the side walls 25 of the container 18, are normally held in closed position against lugs 39, formed on the V-shaped end walls 40 of the container 18 by engagement of a spring clip 41. An opening 42, 10 formed in one of the doors 37, provides for the insertion of a hook or other tool, (not shown), for releasing the doors 37 to permit them to fall into the positions indicated by dotted lines in Fig. 3.

15 In operation, the boom 7 is swung over a car load of anthracite coal, until the receptacle 18 is over the desired location and then lowered to project, or force, the container 18 into the coal to the desired depth. The cable 33 is then operated to release the doors 23, which will fall 20 into the positions indicated by dotted lines in Fig. 3, thus permitting the anthracite coal to enter and fill the receptacle 18. The boom 7 is then raised, until the filled receptacle 18 is clear of the coal in the car, and swung around, 25 until the receptacle 18 is conveniently located on the platform 3. The doors 37 are then opened to permit the anthracite coal in the receptacle to fall onto the platform. After discharging its load of coal, the receptacle 18 is prepared for 30 further operation by slamming the doors 37 closed, and raising the doors 23, releasing the latches 26, and resting the doors 23 on the latches 26.

35 Anthracite coal is generally sampled, as soon as the car leaves the breaker, and the coal is very loosely arranged in the car. In this condition, the anthracite coal offers a minimum of resistance to the insertion of the receptacle 18 and plunger 16. However, if it should be desired 40 to sample a carload of anthracite coal at its destination, instead of at its source, in which case the coal would be more closely packed, the greater resistance offered by the coal may be overcome by the use of a heavier motor, or by 45 oscillation of the boom 7.

45 The important consideration of my invention is to definitely determine the percentage of slate and "bone" in a carload of anthracite coal before it leaves the breakers or mine.

50 At the present time, anthracite coal is cleaned, more or less thoroughly, as it leaves the breakers, with what is known as "Chance", or cone cleaners. This well known cleaner, or piece of apparatus, comprises a fixed cone-shape member, 55 open at the bottom and within which an agitator is located. The anthracite coal, as it leaves the breakers, is fed, or delivered, into the fixed, or stationary, cone-shaped member. An operator, at the same time, applies or supplies the cone-shaped member with steam, under pressure, or 60 a stream of running water, and, from time to time adds sand to the contents of the cone-shaped member. By adding sand to the water and anthracite coal therein, the specific gravity of the mixture of anthracite coal, sand and water can be changed, so that the pieces of washed coal 65 will float over the upper edge of the cone-shaped member, and then delivered to various size mesh of screen for separating, or obtaining, the different sizes, or grades of anthracite coal.

70 During the operation of the "Chance" cleaner; if the specific gravity of the mixture is too low, or the mixture "too thin", the anthracite coal will not readily, or freely, float over the upper edge of the "Chance", or cone-shaped mem-

ber, but some of the coal, with slate and "bone" will be discharged downward through its lower end. On the other hand, if the specific gravity is to be high by adding too much sand, the specific gravity of the mixture will be such that a 5 large percentage of slate, "bone" and sand will flow over the upper edge, with the coal, to the sorting, or screen devices, from which it is delivered into the cars, ready for shipment, or delivery to a customer. In other words, the percentage of slate, "bone" and other impurities is 10 directly controlled, or determined, by the attendant in charge.

15 After the car is loaded with anthracite coal, three samples of its contents, of 20 pounds each, is taken from the upper surface and tested in a laboratory for the percentage of slate, "bone", and other impurities.

20 The result of this test is supposed to indicate to the purchaser that the same percentage of slate, "bone", etc., will be the same through the entire contents of the car of anthracite coal. It has been found, from actual tests made, as the car is being unloaded, that the percentage of slate, "bone", etc., is very often much greater at 25 the middle portion, or bottom of the car, than the previous tests show on the upper surface of the load.

25 The final result of this "Chance" cleaner is that the public is not fully protected, when anthracite coal is cleaned this way.

30 My present invention, therefore, is to accurately determine the percentage of slate, "bone", and other impurities, before the car leaves the breakers for delivery to a customer.

35 My invention, is therefore, designed to obtain samples, as stated, at various points, or parts, of the load, at the breakers, and before it is shipped away from the mines to a customer. If the tests, 40 at the bottom of a load of anthracite coal, do not closely check with the tests on its upper surface, the car is then returned to the "Chance" cleaner for further cleaning.

45 By means of my invention, the customer is always assured of coal, as represented, when it leaves.

What I claim is:—

1. In combination, in an apparatus for obtaining a sample of material for the purpose described, a receptacle, pivotally attached closure means connected to the lower edge of the receptacle, means for normally closing the said closure means, pivotally connected closure means at the upper edge of the receptacle which is in normally closed position, means for inserting the receptacle into a mass of material, means for opening the closure means at the upper edge of the receptacle to allow the material to enter the receptacle, and means for withdrawing the filled receptacle from the mass of material.

2. A receptacle for obtaining a sample of anthracite coal when loaded on a car, discharge doors pivotally connected to the lower portion of the receptacle and located in an inclined position to form a pointed end for easy insertion into the coal, boom means for inserting the receptacle into the coal and removal therefrom, normally closed doors at the upper end of the receptacle for permitting the coal to enter the receptacle when opened, and means for releasing the latter doors after the receptacle has been inserted in the coal, said discharge doors being opened when the receptacle is emptied of its sample contents after withdrawal from the coal, said door-releasing means comprising a tubular member connected 75

to the receptacle, latch means in the tubular member and normally extending under the free edges of the normally closed entrance doors, means for withdrawing the latch means, and means for returning the latch means after being operated.

3. A testing receptacle for anthracite coal comprising, a receiving member, closure doors at its upper end, discharge doors at its lower end and arranged in a V-shaped position when closed, a leaf spring engaging their lower ends for temporarily holding them closed, a tubular member connected to the receptacle, latches therein and normally projecting under the free edges of the closure doors, a spring for retaining the latches in this position, and means for withdrawing the latches to release the closure doors.

4. In combination, in a device for obtaining a

sample of anthracite coal from a loaded car of the same, a pivotally mounted mast arm, a boom member secured to said arm, a hoisting drum, guy wires connected to the drum and boom for raising and lowering the same, a tubular member pivotally secured to and depending from the boom member, a sample receiving receptacle secured to the tubular member, upper closure doors on the receptacle which open inwardly, latch devices in the tubular member for retaining the doors closed, means for operating the latches to release the doors, discharge inclined arranged doors at the lower end of the receptacle, the construction being such that the coal to be sampled will enter the receptacle by gravity when inserted into a mass of coal and the closure doors opened.
